LOUIS BAJETT, OF NEW YORK, N. Y.

CLOTH-SPONGING MACHINE.

1,387,449.

Specification of Letters Patent. Patented Aug. 16, 1921.

Application filed April 30, 1921. Serial No. 465,813.

To all whom it may concern:

Be it known that I, LOUIS BAJETT, a subject of the President of France, and resident of New York, in the county of New York 5 and State of New York, have invented certain new and useful Improvements in Cloth-Sponging Machines, of which the following is a specification.

This invention relates to apparatus for 10 finishing cloth and more particularly to a cloth sponging machine and has special reference to the provision of a machine of this character in which the cloth may be subjected to winding, sponging and rewinding 15 operations in such manner that the shrinking, stretching and wrinkling of the cloth is eliminated to the end that the rewound reel of treated cloth present not only a smooth sponged finish, but that such reel 20 form a compact formation with flat and tightly wrapped layers of unshrunk and unstretched cloth.

One of the difficulties in sponging apparatus of the type referred to has been the 25 practical inability of obtaining a finished cloth reel in which the sponged cloth retain its original characteristics as regards the consistency or density of its weave or its texture, the shrinking or stretching of the cloth 30 incident to the winding, sponging and rewinding operations to which the cloth is subjected having been difficult to overcome. One of the principal objects of my present invention involves the provision of a sponging 35 apparatus in which the cloth to be sponged may be wound, sponged and rewound without liability of being stretched or shrunk, the finished cloth reel having perfectly flat, unwrinkled and tightly wrapped 40 windings of cloth possessing the original characteristics of weave or texture.

In sponging apparatus the usual practice 45 has been to wind the cloth from a cloth reel onto a steam cylinder, the steam cylinder being provided with a multiplicity of perforations in the cylindrical walls thereof, the steam admitted into the cloth wound cylinder discharging through the perforations and permeating the cloth layers or windings for 50 the sponging thereof. The cloth, after being sponged, is wound on other drums for further operations if desired, the cloth being then rewound on its roller in finished condition. I have found that by the provision of 55 apparatus of this type in which the cloth is

wound on the steam cylinder with a sponging web or sheet, the layers of the sheet alternating with the layers of the cloth, that the winding of the cloth onto the cylinder may be so regulated and controlled and that 60 the rewinding of the cloth may also be so regulated and controlled as to prevent stretching of the cloth or the shrinking thereof during such winding or rewinding steps. I have further found that the parts 65 of the apparatus may be so relatively arranged as to permit and afford regulation and control of the winding and rewinding steps in an efficient manner to the end that the resulting finished cloth will present a 70 tightly wound reel formation of unwrinkled cloth having the original weave consistency.

The principal objects of my invention therefore include, besides the provision of apparatus for sponging cloth, the provision 75 of apparatus in which the cloth may be sponged with the original weave or texture thereof maintained; the provision of apparatus in which the parts are so relatively arranged and the elements so controlled as to 80 yield the desired functions; the further provision of an apparatus of this type in which the parts are simple and relatively few in number, and are so arranged as to permit facility of cloth handling and ease of machine 85 operation and the further provision of apparatus of this nature adapted to unwind and rewind removable cloth reels with a minimum of operative steps.

To the accomplishment of the foregoing 90 and such other objects as may hereinafter appear, my invention consists in the elements and their relation one to the other, as hereinafter particularly described and sought to be defined in the claims, reference 95 being had to the accompanying drawings, in which:

Figure 1 is a side elevational view of my apparatus showing the same in use during the winding operation.

Fig. 2 is a front view of the same with parts broken away for the sake of clearness, and

Fig. 3 is a view showing the use of my apparatus during the rewinding operation.

In the process of sponging cloth, the cloth is first unwound from its reel and wound or wrapped about a steam cylinder, this constituting the first winding operation. It is desired in this winding step that 110

the cloth be wrapped about the steam cylinder in a flat, unwrinkled and compact formation, it being further desired that the cloth be thus wound without stretching in order for the cloth to retain, after the subsequent sponging step, its original consistency as regards weave or texture. To obtain these results the cloth is wound about the cylinder in conjunction with a sponging web or sheet, the cloth and the web being wound on the cylinder in alternating layers with the sponging web or sheet fed under properly controlled or regulated tension, the cloth to be sponged being in turn fed to the tensioned web in overlying relation thereto without any direct tension exerted on the cloth itself. To this end I provide a steam cylinder 10 which is journaled in opposed bearings 11 mounted on the table frame work 12, the said cylinder being provided with the usual perforations in the cylindrical walls thereof for the purpose of permitting the discharge of steam from the core of the cylinder through the perforations for permeating the cloth during the subsequent sponging step. For the purpose of carrying the sheet or web windings I provide a drum 13 rotatably mounted in opposed bearings 14, the bearings 14 being mounted on the table 12, as shown more particular in Fig. 1 of the drawings, the drum 13 carrying the windings or convolutions of a sponging web or sheet 15. The axes of the cylinder 10 and the drum 13 are preferably spaced in horizontal alinement and at an elevation from the floor or ground such that these parts will be under ready manual control of an operator, as will appear further hereinafter. The drum 13 is also mounted adjacent the cylinder 10, it having been found desirable as will appear more in detail hereinafter, to provide a short span in the sponging web or cloth between the web windings 15 on the cylinder and the windings on the drum 13. During the winding step the sponging web or sheet is wound under tension from the drum 13 onto the cylinder 10, the cloth 16 to be sponged being fed onto the web, as shown particularly in Fig. 1 of the drawings, the cloth being then wrapped about the cylinder 10 in a flat and unwrinkled state between the windings 15 of the web.

One of the important considerations in the proper feeding of a cloth in the condition desired has been found to be the ability to maintain the web or sheet under the proper tension during the winding operation. I have found that by providing a short controllable span between the cylinder and drum and by controlling or regulating the tension on the drum, that an efficient co-operating web and cloth feed can be maintained to effect the desired results. To this end I provide controllable tensioning means

for the said drum, such tensioning being preferably manually adjustable and comprising preferably a brake drum 17 mounted on one of the side journals 18 of the drum 13, a pivoted brake shoe 19 being provided for co-operation with the said brake drum 17. For the purpose of controlling the tension of the brake elements I provide adjusting means which preferably comprises a pivoted bent arm 20 pivotally mounted on one of the standards 21 of the frame work, the said arm being threaded at its upper end as at 22, the threaded end 22 being received in a suitable bore at an adjacent end of the brake shoe 19, a wing nut 23 being received by the threaded nut 22, the said wing nut engaging the said adjacent end of the brake shoe 19. It will be apparent that in rotating the wing nut in one or the other direction, that tension may be applied to the brake shoe 17 or released therefrom, as may be desired, such tension being controllable and adjustable within the limits found desirable to accomplish the proper tensioning effect on the web or sheet 15.

Means is provided for driving the cylinder 10 to wind thereon the alternate layers of web 15 and cloth 16, such means comprising generally a releasably driven member connected to a driving member forming part of the apparatus. To this end I preferably provide a sprocket wheel 24 fixedly mounted on the shaft 25 of the drum 10, the said sprocket wheel being positively connected to and driven by a sprocket chain 26 and an opposed sprocket wheel 27 mounted on a female clutch member 28, the clutch member 28 being freely rotatable on a driving shaft 29. Splined to the driving shaft 29 for 105 slide movement with respect thereto is a male clutch member 30, the said male clutch member 30 being connected to a clutch lever 31 pivoted to a standard 32. For the purpose of driving the shaft 29 I may provide any main drive or prime mover, the form shown in the drawings contemplating the driving of a shaft 29 by means of a main shaft 33, the said main shaft being driven from a prime mover 34, as by means of belt 110 35 and pulleys or drums 36 and 37, the main shaft 33 being provided with a worm 38 meshing with a worm wheel 39 fixed to the shaft 29. It will be obvious from these machine elements described that the cylinder 10 may be releasably connected to the main driving shaft, the clutch lever 31 being shifted in either direction for this purpose. The clutch elements 28 and 30 which I prefer to use are of the friction clutch type, it having been found that such a clutch is desirable in an apparatus of this type for the reason that if too great a tension is at any moment placed on the drum 13 or the web windings 15, the slipping of the clutch elements 115 120 125 130

will act in the nature of a safety appliance to prevent a too great stretching of the sponging web.

During the winding operation I have found it desirable to support the reel holding the cloth to be sponged 16 in a plane above the horizontal plane of the cylinder and drum, the cloth being fed in flat formation onto the tensioned web or sheet. To this end I provide a supporting structure preferably arranged on opposite sides of the drum 13, the said supporting structure comprising opposed pairs of uprights 40, each pair defining a way 41 therebetween, a bar 42 pivoted on one of the uprights 40 being movable over the way 41, the said bar 42 being provided with a notch 43 adapted to engage a pin 44 mounted on the other of the uprights 40, the said bar 42 when in the position as shown in Fig. 1 of the drawings with the notch thereof engaging the pin 44 serving as a fixed bearing for the journals 45 of the cloth reel 46.

To effect the first winding operation the cloth reel 46 is inserted in the opening bearing provided by the ways 41 with the journals 45 mounted on the fixed bearing elements provided by the bars 42. The leading end of the cloth 16 is then laid flat on the web 15, the cylinder 10 being then rotated to firmly engage such cloth end 16 between the convolutions of the web 15 on the said cylinder 10. The tensioning means provided by the brake shoe 19 and brake drum 17 is then applied, the lever 31 being then moved to effect interengagement of the clutch elements 28 and 30 to place the cylinder 10 in driving connection with the prime mover 34. The tensioning effect of the shoe 19 and drum 17 is then regulated by adjusting the wing nut 23 until the desired tension on the drum is effected, the desired tension being obtained when any vibration in the short span of the web 15 between the cylinder and the drum is eliminated. It has been found that by arranging the steam cylinder 10 and the drum 13 in closely adjacent positionings as shown, with a relatively short web span between these elements, that the tension on the web 15 may be always brought under control and may be adjusted by means of the tensioning devices described, such a correlation of parts and such operation effecting a proper tensioned feed of the web in flat formation, this being an essential criterion for the effective feeding of the cloth 16 in flat, unwrinkled and unstretched form, the arrangement of the cloth reel above the drum 13 with the cloth 16 fed flat and in overlying position onto the web 15 having also been found effective to produce the desired results.

After the cloth 16 has been completely wound onto the cylinder 10, steam is admitted into the cylinder core as usual, the

steam discharging through the perforations in the said core and permeating the cloth for the sponging thereof.

After the sponging step the cloth is rewound on its roller by a reversal of operation of the machine elements described. During the rewinding step it is also desired to prevent stretching of the cloth fiber, it being further desired to so rewind the cloth that no shrinking or wrinkling of the cloth takes place. To accomplish this result I have found it desirable in reversing the drive of the web or sheet to put the sheet again under regulated tension, the sponged cloth being rewound without tension being placed on such cloth, the tension put upon the sheet in conjunction with the rewinding of the sheet serving the purpose of rewinding the cloth without pulling or compacting the fibers thereof to prevent the stretching and subsequent shrinking which often takes place.

For the purpose of placing the proper tension on the sheet or web during such rewinding operation I provide preferably manually controlled elements operative to place tension on the cylinder, the elements being similar in structure and function to the brake shoe and brake drum described in connection with the drum 13. To this end I provide a second brake drum 47 fixedly mounted on the cylinder shaft 25, a brake shoe 48 pivoted as at 49 on the table frame work 12 being provided for co-operation with the said brake drum 47, a threaded bolt 50, wing nut 51 seated against an angle piece 52 being provided for co-operation with the brake drum and brake shoe for the purpose of regulating and adjusting the tensioning effect between the brake elements similar to the regulation of the brake elements described in connection with the drum 13.

For the purpose of effecting rewinding of the now sponged cloth without placing tension directly on the cloth, I mount the roller journals 45 in the guides or ways defined by the uprights 40, the pivoted bar 42 being rotated to open position as shown, for example, in Fig. 3 of the drawings, the mounting of the roller journals being also shown in Fig. 3 of the drawings, the cloth winding 16 on the said roller being in frictional contact with the web windings 15 on the drum 13. By this arrangement the cloth is driven by frictional contact with the rewritable drum 13 and the windings on the drum, the journals 45 of the roller gradually rising in the way 41 between the uprights 40 as the diameter of the cloth reel increases and as the rewinding operation proceeds, the increasing diameter of the cloth reel being shown in dotted lines in Fig. 3 of the drawings. The frictional drive between the reel and the drum windings in conjunction with the feeding of the web 15 under tension dur-

ing such rewinding step has been found efficient in securing a rewound reel of the desired compact formation with the cloth windings in a perfectly flat and unwrinkled 5 state and with the cloth retaining its original consistency of weave or texture.

For the purpose of driving the drum 13 during the rewinding operation, a second releasably driven means is provided releas- 10 ably geared to the main drive shaft in a manner similar to the connections between the cylinder 10 and the said main shaft. To this end the shaft 18 of the drum 13 is provided at an end thereof and preferably 15 at the end opposite to the mounting of the brake drum 17, with a sprocket wheel 53, the said sprocket wheel being positively connected to be driven by the sprocket chain 54 and sprocket wheel 55, the said sprocket 20 wheel 55 being in turn mounted on a female clutch member 56 freely rotatable on the shaft 29. Coöperating with the clutch element or member 56 I provide the male clutch element 57 splined on the shaft 29, the said 25 clutch element being slidably by means of a lever 58 pivoted to a standard 59, the said lever being in turn connected by means of a connecting link 60 to a clutch lever 61 positioned adjacent to the clutch lever 31. 30 The clutch elements 56 and 57 are also preferably of the friction clutch type for coöperation with the tensioned web 15 to prevent extreme tension being placed on such web during the rewinding step.

35 The operation of my improved cloth finishing machine will be apparent from the above detailed description thereof. The cloth reel 46 is mounted with the journals engaging the fixed bearing 42, the leading 40 end of the cloth 16 being inserted between the convolutions of the web 15 on the cylinder 10 as hereinbefore referred to; the tensioning means provided by the cylinder and brake elements 47 and 48 is released to permit 45 free rotation of the cylinder when actuated by the driving means, the tensioning means provided by the drum brake elements 17 and 19 being applied to effect a tension on the web 15, the clutch 31 being then thrown 50 to effect driving action between the drive shaft 29 and the cylinder 10. The cylinder 10 will rotate in the direction shown by the arrow in Fig. 1 of the drawings, alternate layers of the web 15 and cloth 16 being 55 wound about the cylinder, the tension on the web 15 being controlled to a nicety by the adjustment of the drum brake elements, the cloth 16 being thus fed in flat overlying relation on the web 15 without stretching or 60 wrinkling of such cloth taking place. The cloth is then sponged by admitting the steam in the core of the cylinder 10 as is usual, the steam permeating the flat layers of the cloth 16 for the effective sponging thereof. After 65 the sponging step the leading end of the

cloth 16 is wrapped about the cloth roller, the said roller being inserted in the guide or way 41 defined by the uprights 40 with the cloth layer in direct frictional engagement with the layers or convolutions of the web 70 15, as shown in Fig. 3 of the drawings. The brake elements 17 and 19 are then released to permit free rotation of the drum 13 during the rewinding step, the brake means provided by the elements 47 and 48 being then 75 applied and adjusted to effect the desired tension upon the short span of the web 15 between the drum and cylinder layers. At this time clutch 31 is in its disengaged position, clutch 61 being then thrown into en- 80 gaged position to effect a driving coöperation between the shaft 29 and the drum 13. The frictional engagement of the cloth windings with the web windings in coöperation with the regulatable tension applied to 85 the web 15 yields a rewound cloth reel in which the layers assume a tight and perfectly flat form, the cloth 16 rewinding without stretching or compacting of the threads or fibers. 90

It will be apparent from the foregoing that I have provided a cloth finishing means in which the cloth may be subjected to winding, sponging and rewinding operations without liability of cloth stretching or 95 shrinking taking place, the cloth being rewound in a compact state into a reel of flat and smooth cloth having the original characteristics as regards weave or texture. It will be further apparent that I have provided an apparatus having a minimum of parts for accomplishing the desired functions, the parts being arranged in a simple manner yielding a machine capable of ease 100 of operation by a single operative, the relative arrangement of the parts facilitating cloth handling and full control by a single workman. It will be further apparent that the essential machine elements are used to accomplish dual functions, the drum, cylinder and cloth reel supports serving during 105 both the winding and rewinding steps, this securing a minimum of elements for accomplishing all the necessary functions. It will be further apparent that the compact arrangement of the structural elements not only affords facility of control by an operative, but provides a construction in which the regulation of the tensioned parts may be kept "in hand" and controlled to the extent 110 found desirable in practice. It will be further evident that the device as a whole may be used with or without the sponging web or sheet, this being an added feature of the arrangement. Where a cloth is desired to be 115 fed and sponged without the web or sheet, the cloth may be directly wound onto the cylinder and may be rewound by being frictionally driven in contact with the cylindrical faces of the drum 13. 120

130

While I have shown my device in the preferred form, it will be obvious that many changes and modifications may be made in the structure disclosed without departing 5 from the spirit of the invention, defined in the following claims.

I claim:

1. In a cloth sponging apparatus, a rotatable steam cylinder, releasable means for 10 driving the cylinder to wind thereon alternate layers of a sponging web and a cloth to be sponged, a rotatable drum carrying the windings of the sponging web; driving of the steam cylinder being effective to unwind the web drum, releasable provisions 15 for driving the drum to rewind thereon the sponging web and unwind the same from the steam cylinder and supporting means for a reel of cloth to be sponged, said supporting means comprising a unitary structure 20 providing stationary bearings for removably supporting the journals of the cloth reel and utilizable during the winding activity of the cylinder and further providing 25 ways for guiding the said journals and utilizable during rewinding activity of the drum, the cloth reel being frictionally driven by contact with the web windings on the drum during such latter activity.
2. In a cloth sponging apparatus, a rotatable steam cylinder, releasable means for 30 driving the cylinder to wind thereon alternate layers of a sponging web and a cloth to be sponged, a rotatable drum carrying the windings of the sponging web; driving of the steam cylinder being effective to unwind the web drum, releasable provisions 35 for driving the drum to rewind thereon the sponging web and unwind the same from the steam cylinder, the cylinder and drum being spaced to provide a short free span 40 for the windable and rewritable sponging web movable therebetween, and supporting means for a reel of cloth to be sponged, said supporting means including 45 elements for supporting the reel of cloth during the winding and rewinding operations, the supporting means being also spaced from the cylinder to provide a relatively short and free span for the cloth wound and rewound therebetween.
3. In a cloth sponging apparatus, a rotatable steam cylinder, releasable means for 50 driving the cylinder to wind thereon alternate layers of a sponging web and a cloth to be sponged, a rotatable drum carrying the windings of the sponging web; driving of the steam cylinder being effective to unwind the web drum, releasable provisions for 55 driving the drum to rewind thereon the sponging web and unwind the same from the steam cylinder, the cylinder and drum being spaced to provide a short free span 60 for the windable and rewritable sponging web movable therebetween, supporting
- means for a reel of cloth to be sponged, said supporting means including elements for supporting the reel of cloth during the winding and rewinding operations, the supporting means being also spaced from the cylinder to provide a relatively short and free span for the cloth wound and rewound therebetween, and instrumentalities for alternatively tensioning the cylinder and drum, said instrumentalities providing a control for tensioning the free span of the sponging web.
4. In a cloth sponging apparatus, a rotatable steam cylinder, releasable means for 70 driving the cylinder to wind thereon alternate layers of a sponging web and a cloth to be sponged, a rotatable drum carrying the windings of the sponging web; driving of the steam cylinder being effective to unwind the web drum, releasable provisions for 75 driving the drum to rewind thereon the sponging web and unwind the same from the steam cylinder, the cylinder and drum axes being spaced in substantially horizontal alinement, and supporting means for a reel of cloth to be sponged, said supporting means comprising a vertically extending structure radially disposed with respect to the drum axis, the structure providing stationary bearings for the journals of the cloth reel for use during the winding activity of the cylinder and further providing 80 guide ways for the said journals for use during rewinding activity of the drum, the cloth reel being frictionally driven by contact with the web windings on the drum during such latter activity.
5. In a cloth sponging apparatus, a rotatable steam cylinder, releasable means for 85 driving the cylinder, a rotatable drum, releasable provisions for driving the drum, the said means and provisions being adapted for alternate operation to effect winding and rewinding of a cloth to be sponged, the cylinder and drum axes being spaced in substantially horizontal alinement, and means for supporting a reel of the cloth to be sponged; said supporting means comprising uprights arranged on opposite sides of the drum, said uprights being provided with elements constituting fixed open bearings for 90 the journals of the cloth reel during winding activity of the cylinder, the uprights defining guide ways constituting elongated open bearings for the journals during rewinding activity of the drum.
6. In a cloth sponging apparatus, a rotatable steam cylinder, releasable means for 95 driving the cylinder, a rotatable drum, releasable provisions for driving the drum, the said means and provisions being adapted for alternate operation to effect winding and rewinding of a cloth to be sponged, the cylinder and drum axes being spaced in substantially horizontal alinement, and means for 100

supporting a reel of the cloth to be sponged, said supporting means comprising uprights arranged on opposite sides of the drum and radially disposed with respect to the drum 5 axis, the said uprights defining elongated ways for guiding the journals of a cloth reel, the uprights being provided with pivoted elements movable over the guide ways and defining fixed bearing elements for said 10 journals.

7. In a cloth sponging apparatus, a rotatable steam cylinder, means for driving the cylinder to wind thereon alternate layers of a sponging web and a cloth to be 15 sponged, a rotatable drum carrying the windings of the sponging web, driving of the steam cylinder being effective to unwind the web drum, provisions for driving the drum to rewind thereon the sponging web and 20 unwind the same from the steam cylinder, releasable tensioning means for both the cylinder and the drum operative alternately to place the drum under tension during 25 winding activity of the cylinder and to place the cylinder under tension during winding activity of the drum, and supporting means 30 for a reel of cloth to be sponged; said supporting means comprising a structure providing stationary bearings for the journals 35 of the cloth reel utilizable during the winding activity of the cylinder and further providing ways for guiding the said journals and utilizable during rewinding activity of the drum, the cloth reel being frictionally 40 driven by contact with the web windings on the drum during such latter activity.

8. In a cloth sponging apparatus, a rotatable steam cylinder, yieldable releasable 45 means for driving the cylinder to wind thereon alternate layers of a sponging web and a cloth to be sponged, a rotatable drum carrying the windings of the sponging web; driving of the steam cylinder being effective to unwind the web drum, yieldable releasable provisions for driving the drum to 50 rewind thereon the sponging web and unwind the same from the steam cylinder, releasable tensioning means for both the cylinder and the drum operative alternately to place 55 the drum under tension during winding activity of the cylinder and to place the cylinder under tension during rewinding activity of the drum, and supporting means for a reel of cloth to be sponged; said supporting means comprising a structure providing 60 stationary bearings for the journals

of the cloth reel utilizable during the winding activity of the cylinder and further providing guiding ways for the said journals utilizable during rewinding activity of the 60 drum, the cloth reel being frictionally driven by contact with the web windings on the drum during such latter activity.

9. In a cloth sponging apparatus, a rotatable steam cylinder, releasable means for 65 driving the cylinder, a rotatable drum, releasable provisions for driving the drum, the said means and provisions being adapted for alternate operation to effect winding and rewinding of a cloth to be sponged, the 70 cylinder and drum axes being spaced in substantially horizontal alinement, releasable tensioning means for both the cylinder and the drum operative alternatively to place the drum under tension during winding activity of the cylinder and to place the cylinder under tension during rewinding activity of the drum, and means for supporting a reel of the cloth to be sponged, 75 said supporting means comprising uprights 80 arranged on opposite sides of the drum, said uprights being provided with elements constituting stationary bearings for the journals of the cloth reel during winding activity of the cylinder, the uprights defining 85 guide ways constituting elongated open bearings for the journals during rewinding activity of the drum.

10. In a cloth sponging apparatus, a rotatable steam cylinder, releasable means for 90 driving the cylinder, a rotatable drum, releasable provisions for driving the drum, the said means and provisions being adapted for alternate operation to effect winding and rewinding of a cloth to be sponged, the 95 cylinder and drum axes being spaced in substantially horizontal alinement, releasable tensioning means for both the cylinder and the drum operative alternatively to place the drum under tension during winding activity of the cylinder and to place the cylinder under tension during rewinding activity of the drum, and means for 100 supporting a reel of the cloth to be sponged, said means comprising provisions for alternatively supporting the journals of the cloth reel during winding and rewinding activity of the apparatus.

Signed at New York, in the county of New York and State of New York, this 110 28th day of April, A. D. 1921.

LOUIS BAJETT.
